(57) **CLAIM**

The ornamental design for a beverage machine, as shown and described.

DESCRIPTION

FIG. 1 is a front left perspective view of my new, original and ornamental design;

FIG. 2 is a front elevational view thereof;

FIG. 3 is a right side elevational view thereof;

FIG. 4 is a rear elevational view thereof;

FIG. 5 is a left side elevational view thereof;

FIG. 6 is a top plan view thereof; and,

FIG. 7 is a bottom plan view thereof.

The broken lines in the drawing depict portions of the beverage machine that form no part of the claimed design.
